[57] ABSTRACT

An electric lantern has a case in two portions which may be opened to permit replacement of batteries without disengagement of the other components from the upper portion of the case. Means are provided to retain the lamp and upper portion of the battery case as retained members of a structurally engaged assembly which may be disengaged from the lower portion of the battery case. As a separate feature, a lens may be disengaged from the battery case to permit replacement of the electric lamp without opening the battery case. A rod is used as a member of the engagement means which hold the lantern components together; in addition, the rod may be part of the lantern's electrical circuit. The electrical circuit may be designed so that it is opened when the battery case is opened and/or when the lens is disengaged from the battery case.

BATTERY POWERED ELECTRIC LANTERN

BACKGROUND OF THE INVENTION

To the campers, hikers, hunters and others who use battery powered electric lanterns, it is important to be able to open the lantern to replace consumed batteries or lamps with a minimum of effort and time. It is also important that the lantern be designed to be opened so that a minimum number of parts or subassemblies are disengaged, for there is always the danger of losing or misplacing one of the parts while the batteries or lamp is being replaced. Finally, it is desirable to design the lantern so that its user cannot accidentally receive an electrical shock in the process of trying to replace the batteries or lamps.

SUMMARY OF THE INVENTION

The lantern of this invention includes a battery case which contains at least one battery, with the case itself comprising an upper portion and a lower portion. Means are provided for permitting the upper and lower portions of the battery case to be engaged and disengaged. A rod secured to the upper portion of the battery case may be used as a component of this battery case engagement means.

Responsive to the needs of campers and other users, the lantern may be provided with engagement means for retaining the lamp and upper portion of the battery case as members of a structurally engaged assembly which is held together while the upper and lower portions of the battery case are disengaged from each other. The lantern may also be designed so that a lens surrounding the lamp can be disengaged from the battery case while the upper and lower portions of the battery case remain engaged together. Thus the danger of having parts scattered and possibly lost is minimized when the camper needs to open the lantern to replace batteries or a lamp. In certain embodiments the rod comprises a member of the engagement means which secure the lens to the upper portion of the battery case.

The rod is included as a component of the electrical circuit in certain embodiments of the lantern. As a safety feature the circuit may be designed to be opened when the upper and lower portions of the battery case are disengaged from each other and/or when the lens is disengaged from the battery case.

BRIEF DESCRIPTION OF THE DRAWINGS

FIG. 1 is a perspective view of a fully assembled battery powered electric lantern containing the features of this invention.

FIG. 2 is a partially exploded view of the lantern appearing in FIG. 1, showing the lens and hood disengaged from the battery case while the upper and lower portions of the battery case are engaged together.

FIG. 3 is a partially exploded view of the lantern appearing in FIG. 1, showing the upper and lower portions of the battery case disengaged from each other while the lens and hood engagement means retain the upper portion of the case, the lens, and the hood in engagement with each other.

FIG. 4 is a section of the lantern appearing in FIG. 1, with batteries removed.

FIG. 5 is a perspective view showing the electrical components of the lantern appearing in FIG. 1.

FIG. 6 is an electrical circuitry diagram of the lantern appearing in FIGS. 1 and 5.

FIG. 7 is an elevational view of another battery powered electric lantern containing features of this invention.

FIG. 8 is a section of the lantern appearing in FIG. 7.

FIG. 9 is a front elevational view of another battery powered electric lantern containing features of this invention.

FIG. 10 is a side elevational view of the lantern appearing in FIG. 9.

DESCRIPTION OF THE PREFERRED EMBODIMENTS

The invention will first be explained and illustrated by references to one particular model of the battery powered electric lantern, the model appearing in FIGS. 1-6. Later two other models containing features of the invention (shown in FIGS. 7 and 8 and FIGS. 9 and 10, respectively) will be described.

FIGS. 1-4 illustrate a battery powered electric lantern 10 having a case 12 comprising an upper portion 14 and a lower portion 16 whose surfaces complement each other and mate together in a predetermined manner. The walls of the case 12 define a space inside the case for housing at least one battery 18 (four such batteries 18 are shown in FIG. 3). The lantern 10 includes a rod 20 which extends from the interior to the exterior of the battery case 12. Other components of the lantern include a transparent lens 22 fitted into a groove 23 near the top of the upper case portion 14, at least one electrical lamp 24 (two such lamps 24, 24 L and 24 R, are shown in FIGS. 1-4) inside the lens 22, a hood 26 which fits snugly over the top of the lens 22 and which may be provided with a handle 28 for easy carrying, and an electrical circuit connecting the batteries 18 with the lamps 24.

The lantern 10 is provided with battery case engagement means for permitting the upper and lower portions of the battery case to be engaged and disengaged. While these battery case engagement means may include such items as clasps or buckles (not shown in the drawings), they preferably include the rod 20 in a manner to be described below. The rod may also be a component of engagement means which retain the lamps 24 and the upper portion of the battery case together as members of a structurally engaged assembly when the upper and lower portions of the battery case are disengaged from each other. The lantern 10 also has means which allow the lens 22 to be disengaged from the battery case 12 so that the lamps 24 may be replaced without opening the battery case (see FIG. 2), and the rod 20 may be included in these means. The lantern 10 is also provided with lens and upper battery case engagement means for retaining the lens 22 upper portion 14 of the battery case 12 as members of a structurally engaged assembly 29 (see FIG. 3) while the upper and lower portions of the battery case 12 are disengaged to permit battery replacement; the rod 20 is included in these means.

These several engagement means are illustrated in FIGS. 2-4, particularly FIG. 4. The threaded lower end of the rod 20 is screwed into a threaded member 30 secured in a fixed position to the lower case portion 16. Extending upward from this threaded member 30, the rod 20 passes first through an opening 32 in a disc 34 and then through an opening 36 at the top of the upper case portion 14. Means such as retainer rings 38 and 40 are fixed with respect to the rod 20 and are secured to

and bear against the top and bottom surfaces 42 and 44, respectively, of a depending projection 46 of the disc 34, while additional retainer means 48 are secured to and fixed with respect to the rod just above the opening 36 in the upper case portion 14; collectively these means 38, 40 and 48 cooperate with the rod 20, the disc 34, and the upper case portion 14 in such a manner that the disc is structurally engaged with and drawn snugly against the inner surface of a shoulder 50 of the upper case portion 14 while the rod may be rotated but not moved vertically with respect to the disc 34 and upper case portion 14. Projecting further above the battery case, the rod 20 extends upward through the lens and out through an opening 52 of the hood 26. The hood 26 has a shoulder 54 which structurally engages the upper edge of the lens 22. A knob 56, which is provided with a centrally located opening 58 of a generally rectangular configuration and size matching that of the upper end of rod 20, fits over and engages the upper end of rod 20 so that a rotation of the knob 56 produces a simultaneous rotation of the rod 20. A securing device such as a closed nut 60 is screwed onto the upper extremity of the rod 20 and prevents removal of the knob 56 from the rod 20 without prior detachment of the nut 60. The knob 56 and the rod 20 may be rotated with respect to the opening 52 of the hood 26. By causing the nut 60 to bear snugly against the top of the knob 56, the knob 56 bears snugly against the top of the hood 26 which in turn bears against the upper edge of the lens 22, which causes the lower edge of the lens 22 to bear against the upper case portion 14. As shown in FIG. 2 and as described above, by simply unscrewing the nut 60 and lifting upward on the knob 56, hood 26, and lens 22, the electric lamps 24 may be exposed and replaced without rotating the rod and disengaging the upper and lower portions of the battery case.

A proper rotation of the knob and the rod causes the upper and lower portions 14 and 16 of the battery case 12 to be drawn together at their mating surfaces; a rotation of the knob 56 in the opposite direction will cause the two portions of the battery case to become disengaged while the hood, lens, and upper portion of the battery case remain engaged as members of assembly 29. As shown in FIG. 3 and as described above, it will be seen that the structurally engaged assembly 29 may be engaged with or disengaged from the lower portion 16 of the battery case 12 to permit battery replacement by simply rotating the knob 56 while the nut 60 remains threaded onto the top of the rod 20.

The electrical components and circuitry for the lantern shown in FIGS. 1-4, which utilizes lamps 24, are illustrated in FIGS. 5 and 6. Mounted onto the lower surface of disc 34 (not shown in FIG. 5) are four conductive members 62 which make contact with the terminals of the batteries 18 and connect the batteries when the upper and lower portions of the battery case 12 are in engagement with each other. With this feature the electrical circuit between the batteries and the lamps is opened when the lower portion of the battery case is disengaged from the upper portion of the case. A pair of conductive wires 64 connect the terminals of the batteries with an inverter 68 situated inside the upper case portion 14 above the disc 34 where the electrical energy is converted from DC to high voltage AC. The circuitry of the lamp includes a pair of switches 72 and 74, shown in FIGS. 1-5, with the switch 72 having three positions ("off," "1 lamp," and "2 lamps," as

shown in FIG. 5) and the switch 74 having two positions ("bright" and "dim"). (In FIG. 4 the switches 72 and 74 have been rotated to appear in profile at the left, rather than being shown as required by a true orthographic projection.) With switch 72 in the "off" position, the inverter is de-energized and no electrical energy reaches either lamp. With switch 72 in the "1 lamp" position, electrical energy flows from the inverter through a conductive wire 76 to and through conductive, spring biased contact 78 in contact with the base of lamp 24 L to and through a conductor 80 secured to a disc 81 situated at the top of and inside the lens 22 (as shown in FIG. 4) which conductor is biased against and in contact with metal rod 20; from the conductor 80 to the rod 20; and from the rod 20 via a biased metal conductor 82 (mounted atop disc 34) and a conductive wire 84 back to the inverter. Thus it can be seen that the rod is included in the lantern's electrical circuit. With switch 72 in the "2 lamp" position, electrical energy from the inverter flows up through lamp 24 L, across conductor 80 and rod 20 to another conductor (also biased against and in contact with rod 20), and down through lamp 24 R.

Another feature which may be included in the lantern's electrical circuit as a safety feature is a switch 88, shown in FIG. 2, located near the top of the upper case portion 14 in a position directly beneath the lower edge of the lens 22. The lantern is constructed so that the lens 22 closes the switch 88 and the lantern's electrical circuit when the lens 22 is in engagement with the upper portion of the battery case, but the electrical circuit is opened when the lens 22 and the hood 26 are disengaged from the battery case. This safety feature prevents a person from getting a shock from the lantern's power source while changing lamps 24.

Many details of the lantern described above can be varied without departing from all aspects of the present invention. The use of a protective lens around the lamp can be excluded if desired. A hood is also optional, with the one shown and described above being for purposes of protection as well as a component of the lens and upper battery case engagement means; these functions can either be excluded altogether or built into the lens if desired. A wide variety of electrical circuits can be designed for use in the lantern, not all of which include the rod as a component of the circuitry. The details shown in the drawings and described above are merely illustrative of a preferred embodiment of the invention; many other embodiments are also possible.

Another model of lantern containing embodiments of this invention is shown in FIGS. 7 and 8. That lantern 100 is in many respects constructed similarly to the lantern 100 shown in FIGS. 1-6, and corresponding parts of lanterns 100 and 10 will be identified with character numbers having the same last two digits, e.g., battery case 12 having upper and lower portions 14 and 16, respectively, of lantern 10 correspond and are substantially identical with battery case 112 having upper and lower portions 114 and 116, respectively, of lantern 100. The absence of such correspondence in character numbers between parts of lanterns 10 and 100 may generally be taken to mean that there are not corresponding parts or functions in the two lanterns. Only the significant differences between the two lanterns will be described in the following discussion of lantern 100.

Lantern 100 has a lens 122, a lamp 124, and a hood 126 which are generally circular in configuration. The

lamp 124 is situated in the enclosed space defined by the mating transparent lens 122 and opaque hood 126. The lantern 100 is constructed so that when the closed nut 160 is unscrewed from the threaded top of the rod 120 and the knob 156 is removed, the lens 122, the lamp 124, and the hood 126 may be lifted up and removed as a single illuminating unit 129. The handle 128 attached to the top of the hood 126 may act both as a carrying handle for the fully assembled lantern and as a hanger to permit the illuminating unit 129 to be held by hand or to be hung or suspended from a hook at the top of a tent, trailer, or cabin. The wires 176 carrying current to the lamp 124 are purposely made relatively long so that the distance between the illuminating unit 129 and the remainder of the lantern can be made great; for instance, the illuminating unit 129 may be hung at the top of a tent or cabin while the remainder of the lantern rests on the ground or floor. These wires 176 may be coiled and stored inside the opaque, generally cylindrical sleeve 125 (corresponding in position but not in function to the lens 122 of lantern 10) which is positioned between the illuminating unit 129 and the battery case 112.

The electrical circuitry of lantern 100 may be made somewhat simpler than the circuitry of lantern 10. Since there is one lamp 124 rather than two as in lantern 10, the lantern 100 may use only a single switch 173 having, if desired, three positions, "off," "bright," and "dim." The rod 120 is not used as a component of the electrical circuitry in lantern 100. In the same manner as with lantern 10, lantern 100 is designed so that by rotating knob 156 (which produces a rotation of rod 120) the hood 126, the lamp 224, the lens 122, the cylindrical sleeve 125, and the upper battery case portion 114 may be retained as a structurally engaged assembly while the upper and lower portions of the battery case 112 are disengaged from each other; when this occurs the conductive members 162 (not shown in FIGS. 7 and 8; see corresponding parts 62 in FIG. 5) are disengaged from the terminals of the batteries and the electrical circuit between the batteries and the lamp 124 is opened.

Still another model of lantern containing embodiments of this invention is shown in FIGS. 9 and 10. That lantern 200 is in many respects constructed similarly to the lanterns 10 and 100 shown in FIGS. 1-6 and 7-8, respectively, and where correspondence exists, the parts of lantern 200 will be identified with character numbers having the same last two digits as the corresponding parts in lanterns 10 and 100. The discussion of lantern 200 to follow below will focus primarily on the features which are found in lantern 200 but not in the other models and on the differences between lantern 200 and lanterns 10 and/or 100.

Lantern 200 has an illuminating unit 229 similar in most respects to the corresponding unit 129 of lantern 100. That unit 229 comprises a lamp 224 situated in the enclosed space defined by the mating transparent lens 222 and opaque hood 226, with the unit 229 being provided with a carrying handle 228. Unlike the corresponding unit 129 of lantern 100, the illuminating unit 229 of lantern 200 is not detachable, but is rotatable, with respect to the remainder of the lantern by virtue of the fact that it is rotatably secured to and between a pair of arms 275 which are joined to the top of upper case portion 214. The electrical wires 276 which carry current from the batteries to the lamp 224 are shown in

FIG. 9 as being enclosed inside a transparent plastic film 277 which is fitted tightly around one of the arms 275.

Referring to the specific illuminating unit 229 shown in FIGS. 9 and 10, the area inside the circular lens 222 and lamp 224 is provided with a mirror 231 to permit a camper to see while shaving, pinning up hair, etc.; alternatively, this area may be left unoccupied or may be equipped with electrical appliances such as radios, 10 fans, insect sprayers, etc., which also draw power from the lantern's batteries.

Except for the differences noted above, the lantern 200 is substantially identical in construction with lantern 100. Lantern 200 may use only a single switch 273 having, if desired, three positions, "off," "bright," and "dim." The rod 220 (not shown in FIGS. 9 and 10) which extends from the interior to the exterior of the battery case 212 is not used as a component of the electrical circuitry in lantern 200. Lantern 200 is designed so that by rotating knob 256 (which produces a rotation of rod 220) the hood 226, the lamp 224, the lens 222, the arms 275, and the upper battery case portion 214 may be retained as structurally engaged assembly while the upper and lower portions of the battery case 212 are disengaged from each other; when this occurs the conductive members 262 (not shown in FIGS. 9 and 10; see corresponding parts 62 in FIG. 5) are disengaged from the terminals of the batteries and the electrical circuit between the batteries and the lamp is opened.

One final difference between lantern 200 and lanterns 10 and 100: since there is no need to remove the knob 256 to permit replacement of the lamps (as in lantern 10) or to remove the illuminating unit (as in lantern 100) there is no need to have a detachable securing device such as a closed nut (item 60 in lantern 10, item 160 in lantern 100). The lantern 200 is therefore provided with a securing device 261 which is permanently affixed to the top of rod 220 to prevent removal of knob 256. Knob 256, therefore, may be rotated to produce a rotation of rod 220, but it may not be lifted off of rod 220.

Having explained our invention, we claim:

- 45 1. A battery powered electric lantern comprising the combination of:
  - a. a battery case, the case comprising an upper portion and a lower portion and defining a space inside the case for housing at least one battery;
  - b. battery case engagement means for permitting the upper and lower portions of the battery case to be engaged and disengaged, the battery case engagement means comprising
    - i. a rod secured to the upper portion of the case and extending into the interior of the case, and,
    - ii. means secured to the lower portion of the case and engaging the rod inside the case;
    - c. at least one battery inside the case;
    - d. at least one electric lamp;
    - e. lamp and upper battery case engagement means for retaining the lamp and upper portion of the battery case together as members of a structurally engaged assembly when the upper and lower portions of the battery case are disengaged from each other; and,
    - f. an electrical circuit connecting the battery with the lamp.

2. The lantern of claim 1 in combination with a lens surrounding the lamp, the lantern being further described as having means including the rod for engaging the lens with the upper portion of the case as a structurally engaged assembly when the upper and lower portions of the battery case are disengaged from each other.

3. The lantern of claim 2 in which the rod comprises a member of the lamp and upper battery case engagement means.

4. The lantern of claim 3 in which the electrical circuit includes the rod.

5. The lantern of claim 2 in which the electrical circuit includes the rod.

6. The lantern of claim 5 in which the electrical circuit between the battery and the lamp is opened when the lower portion of the battery case is disengaged from the upper portion of the case.

7. The lantern of claim 2 in which the electrical circuit between the battery and the lamp is opened when the lower portion of the battery case is disengaged from the upper portion of the case.

8. The lantern of claim 2 in which the electrical circuit includes a switch which closes the circuit when the

lens is in engagement with the upper portion of the case and opens the circuit when the lens is not in engagement with the upper portion of the case.

9. The lantern of claim 2 in which the electrical circuit includes a switch which closes the circuit when the lens is in engagement with the upper portion of the case and opens the circuit when the lens is not in engagement with the upper portion of the case.

10. The lantern of claim 1 in which the rod comprises a member of the lamp and upper battery engagement means.

11. The lantern of claim 10 in which the electrical circuit includes the rod.

12. The lantern of claim 1 in which the electrical circuit includes the rod.

13. The lantern of claim 12 in which the electrical circuit between the battery and the lamp is opened when the lower portion of the battery case is disengaged from the upper portion of the case.

14. The lantern of claim 1 in which the electrical circuit between the battery and the lamp is opened when the lower portion of the battery case is disengaged from the upper portion of the case.
